ATTORNEY

UNITED STATES PATENT OFFICE.

THOMAS J. MADIGAN, OF BROOKLYN, NEW YORK.

CURRENT-CONTROLLING DEVICE.

Application filed May 12, 1926. Serial No. 108,486.

This invention relates to improvements in current controlling devices and more particularly to automatic switches for electric heating devices such as flat irons.

5 The primary object of the invention is to prevent the continued flow of electric current and accompanying waste when the instrument is not in use.

A more specific object of the invention is 10 to prevent overheating of the instrument with the accompanying dangers such as the burning out of the heating element and possible injury to the work.

One feature of the invention is the automatic cutting off of the current when the instrument is flat on the work, and the switching on of the current when the instrument is tilted back.

Another feature of the invention is the 20 articulation of the switch handle which enables the user to fold the grip portion back upon itself and out of the way of the hand so that the current may be disconnected even while the device is in use.

25 A further feature of the invention is the universal connection between the contact member and the switch element which permits of its application to instruments having a variety of handle arrangements.

30 In the drawings:

Figure 1, is a side view of an electric flat iron equipped with this improved current control device, and

Figure 2, is a rear end view of Figure 1.

35 Referring to the drawings in detail, the iron consists of a body 10 provided with the customary handle 11 and handle support 12. The handle is secured to the support 12 by means of a longitudinal screw 13 and nut 14. The usual terminal studs 15 project 40 upwardly from the body 10 near its rear end, and secured to the rear leg of the handle support is the customary sheath 16 for the reception of the plug usually connected 45 to the end of the conductor cord.

This improved switch 17 is secured at the back of the rear leg of the handle support 12 by means of the bolt 18 and nut 19, and pivoted to the switch 17 is a lever 20 which 50 when moved in a direction toward the iron operates the switch mechanism to complete the circuit through the iron. A grip portion 19 is pivoted at 20 to the lever 18 and lies longitudinally of the handle in such a position 55 that when the handle is grasped, the switch will be moved to "on" position, and

as soon as the pressure is released, the lever will return to "off" position through the action of the spring and plunger 21 and 22 respectively.

It is recognized that the angular relations of the various parts of irons of different manufacture will vary and in order to permit the device to be universally used, a separate plug 23 is connected to the switch 17 65 by means of a short length of flexible conductor cord 24.

In use the plug 23 is slipped over the terminal studs 15 and into the sheath 16. The screw 13 is then partly withdrawn and the end passed through the supporting member 25 of the switch 17 and the nut 14 drawn up tight. In this manner the parts will be firmly held in proper position irrespective of the position of the terminal plugs 15. 70 Obviously as soon as the handle is grasped by the user, the grip 19 will be advanced toward the iron thus manipulating the switch and causing current to flow through the iron. As soon as the grip on the handle 75 is released, the lever 18 will return to its original position, thus breaking the circuit. Should the iron become too hot, it is but necessary to fold the grip 19 back on its pivot 20 and out of the way of the handle 80 11. When it is desired to heat the iron without holding the handle, it is only necessary to tilt it backwards until the back of the lever 18 engages the table or other support. When in this position it will be seen 85 that the lever will be moved so as to operate the switch and complete the circuit.

What is claimed is:

1. The combination with an electrical heating instrument, of an automatic switch 95 to discontinue the flow of current therethrough when the instrument is at rest, said switch including a body fixed at the rear of the instrument, a lever hingedly engaged to said body to make contact with a surface when the instrument is stood upon its rear end, resilient means in said body to press said lever outwardly, and means carried by said lever to control said switch.

2. The combination with an electrical 105 heating instrument, of a switch removably secured thereto, a universal connection between the switch and the instrument to permit the switch to be used with instruments of different structural details and a spring 110 actuated control lever pivoted to said switch to extend normally at a right angle to the

base of said instrument to partially support the same when the instrument is in an upright position.

3. The combination with an electric flat iron having a handle and conductor studs, of a switch attached directly to the handle, a plug universally connected to the switch for establishing contact between the studs and the switch, a spring pressed control lever pivoted to said switch to make contact with a surface when the iron is stood upon its rear end, and a second lever pivoted to the end of the first named lever to fold over its outer side or to be extended over said handle.

4. An electrical current controlling device comprising a switch, a lever for moving the switch to complete an electric circuit, a manually operable lever pivoted to the end

of the first named lever to extend towards the front or towards the rear, means to normally hold the switch levers in position to break the circuit and an attachment plug universally connected to the switch.

5. The combination with an electric current consuming device, of spring impelled lever means to automatically discontinue the flow of current therethrough when it is in a state of rest, a handle grip for controlling the flow of current through the device, and a pivot connecting said handle grip to the lever means whereby the handle grip may be thrown into and out of operative position.

Signed at New York, county of New York, State of New York, this 8th day of May, 1926.

THOMAS J. MADIGAN.
